UNITED STATES PATENT OFFICE.

JOSEPH FISHER, OF BROOKLYN, NEW YORK, ASSIGNOR, BY DIRECT AND MESNE ASSIGNMENTS, TO THOMAS W. THOMPSON AND CHARLES H. WOELTJE, OF SAME PLACE.

DESIGN FOR A BICYCLE-TOOL.

SPECIFICATION forming part of Design No. 27,659, dated September 21, 1897.

Application filed March 30, 1897. Serial No. 629,984. Term of patent 3½ years.

To all whom it may concern:

Be it known that I, JOSEPH FISHER, a citizen of the United States, and a resident of Brooklyn, in the county of Kings and State 5 of New York, have invented and produced a new and original Design in a Convertible Implement, of which the following is a specification.

The leading feature of my design consists 10 of the general contour, which I shall fully describe hereinafter.

The frame *a* of the structure forms the handle of the bicycle-tool, and the upper portion terminates in a wrench-shaped hammer-head *k*. One edge (indicated by the letter 15 *d*) is mounted with a cylindrical-shaped projection *e*, arranged longitudinally with said edge *d*. The edge indicated by *b* is provided with a longitudinally-arranged slot containing 20 a correspondingly-shaped strip *c*. The lower portion of the frame *a* is provided with

a rectangular-shaped opening *f*, which contains a correspondingly-shaped body *g*, the latter of which is provided with a depending stem *h*, slightly tapering. The lower end of 25 the said stem *h* enters or is connected with a knurl-shaped knob *i*, located on the end of the said frame *a*. The body of the frame *a* is also provided with a knurled cylindrical projection *l*. 30

What I claim is—

The design for a bicycle-tool herein shown and described.

In testimony that I claim the foregoing as my invention I have signed my name, in presence of two witnesses, this 12th day of March, 1897. 35

JOSEPH FISHER.
